(57) **CLAIM**

The ornamental design for a lamp, as shown and described.

DESCRIPTION

FIG. 1 is a perspective view of an embodiment of the ornamental design of a lamp.

FIG. 2 is a perspective view of another embodiment of the ornamental design of the lamp.

FIG. 3 is a perspective view of another embodiment of the ornamental design of the lamp.

FIG. 4 is a top view of an embodiment of the ornamental design of the lamp.

FIG. 5 is a top view of an embodiment of the ornamental design of the lamp.

FIG. 6 is a top view of an embodiment of the ornamental design of the lamp.

FIG. 7 is a side view of an embodiment of the ornamental design of the lamp.

FIG. 8 is a front/back view of an embodiment of the ornamental design of the lamp.

FIG. 9 is a bottom view of an embodiment of the ornamental design of the lamp.

FIG. 10 is another perspective view of an embodiment of the ornamental design of the lamp.

FIG. 11 is a perspective view of another embodiment of the ornamental design of the lamp.

FIG. 12 is a top view of another embodiment of the ornamental design of the lamp.

FIG. 13 is a side view of another embodiment of the ornamental design of the lamp.

FIG. 14 is a front/back view of another embodiment of the ornamental design of the lamp.

FIG. 15 is a bottom view of another embodiment of the ornamental design of the lamp.

FIG. 16 is another perspective view of another embodiment of the ornamental design of the lamp.

FIG. 17 is another perspective view of another embodiment of the ornamental design of the lamp.

FIG. 18 is another top view of another embodiment of the ornamental design of the lamp.

FIG. 19 is another perspective view of another embodiment of the ornamental design of the lamp; and,

FIG. 20 is another top view of another embodiment of the ornamental design of the lamp.

The broken-line disclosure in the views is understood to represent portions of the article in which the claimed design is embodied, but which form no part of the claimed design.

1 Claim, 20 Drawing Sheets
